UNITED STATES PATENT OFFICE

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY

METHOD FOR USE IN THE MANUFACTURE OF SHOES

Application filed January 18, 1926. Serial No. 82,029.

This invention relates to methods of manufacturing shoes and is herein set forth by way of exemplification merely in its application to shoes in which the upper and out-
5 sole are attached together by through-and-through stitching, it being understood that in many of its aspects it is applicable to the manufacture of shoes of other types.

In the manufacture of fine shoes for women
10 a neat and trim appearance of the shank portion is highly desirable, and, contributing to this, a "thin edge" shank and a "close" shank are important. That is, the sole must be thin at the edge of the shank portion to form a
15 "thin edge" shank and the margin of the sole must lie close to the upper to form a "close" shank.

The operation of shaping the shank if the transverse curvature is pronounced, as it is
20 in most women's shoes, is not readily carried out by means of a leveling roll such as is commonly used in sole leveling machines because the leveling roll is apt to strike the side of the last before it can act to bend the
25 margin of the sole sufficiently to bring it close to the upper, as required for forming a close shank. By the use of a shank beating machine after the leveling, better results may be secured, but this is extremely laborious for
30 the operator. On the other hand, the use of direct pressure leveling, by which pressure is applied simultaneously to the shank and forepart of a shoe bottom, requires a very expensive equipment of iron lasts and corre-
35 sponding sole molds which, in order to secure good results, must be very carefully made and the use of which, if uniform pressure is to be obtained, requires exact similarity in the bottoms of different shoes.

40 Objects of this invention are to provide for obtaining readily and at small expense the bottom shaping effects referred to. In one aspect the invention consists in performing the sole-leveling operation in two separate
45 steps or stages, in one of which one section of the shoe bottom is operated upon and in the other of which another section of the shoe bottom is treated. For example, in one step the forepart of the shoe may be sub-
50 jected to pressure applied in a transverse

band, which band is caused to travel longitudinally of the shoe, to and fro from the toe end to the ball line, thus subjecting the entire forepart progressively to leveling pressure. Then, as another step, powerful forming pressure may be applied to all parts of the entire shank portion of the sole simultaneously, which pressure is preferably concentrated especially upon the margins of the shank portion of the sole. In order effectively
55 to force the margins of the sole against the upper at those portions which are adjacent to the ball line, the pressure upon the shank may be effected in an upward and forward direction with respect to the shoe.
60

In the treatment of the forepart, which is readily effected, for example, by means of a roll, there may be a displacement of the material of the sole toward the ball; hence the formation of a more or less well-defined
65 ridge at the ball where the relative traverse of the roll and the forepart ends. In order that the ridge of material shall coincide with the ball line, the axis of the roll is preferably arranged substantially parallel to the ball line. Thus, the pressure applied at different parts adjacent to the ball line will be
70 uniform and there will be no danger of the roll going beyond the ball line at any point.
75

The pressure applied to the shank portion
80 may be allowed to overlap the ball line and the pressure member may be so formed as either to define and accentuate the ball line, as is sometimes required, or to obliterate the line of demarcation between the shank and the ball and effectively smooth down the ridge of material piled up adjacent to the ball line by the action of the roll.
85

In the treatment of shoes in which the surface upon which the outsole is laid is more or less irregular and uneven as it is, for example, in most shoes which are stitched through and through, it is desirable that the band of pressure applied to the forepart be broad lengthwise of the shoe, so that it will
90 not follow the small irregularities which may occur in the shoe bottom but will act as the band progresses lengthwise of the shoe to impart thereto an even and regular surface.
95 This result is obtained, as herein disclosed,
100

by employing a roll of relatively large diameter so that the area of contact of the roll with the shoe bottom is in the form of a broad band as distinguished from a relatively narrow band produced by a small roll such as required when the action of the roll is applied to the shank as well as the forepart. A further distinct advantage attendant upon the use of a large roll is that the relative movements between the roll and the shoe do not need to be so carefully adjusted to avoid the action of the roll extending beyond the ball line or to prevent the roll from dropping off the shoe at the toe or damaging the toe end of the sole in passing on or off the shoe. There is also usually under the toe portion of the sole bunched material formed by gathering the upper in lasting which, even after it has been reduced by trimming and pounding operations, is apt to project somewhat beyond the general level of the shoe bottom. The broad band of pressure produced by the large roll is particularly effective in dealing with this condition, since it is wide enough to extend over substantially the whole of the bunched portion and to span the cavity usually found at the rear of the bunch.

In another aspect the invention consists in applying to one end of the forepart pressure treatments which are not applied to the remainder of the forepart. For example, the pressure may be made to travel back and forth repeatedly at one end of the forepart alternately with the movements which carry the band the entire length of the forepart. As herein illustrated, the roll by which the band of pressure is applied is caused, by relative movement of the roll and the shoe, to progress lengthwise of the shoe and to traverse the length of the forepart from toe to ball line twice in each direction in each leveling operation and to progress from one end of the forepart part way toward the other end and back a plurality of times, for example, so many times in addition that one end portion of the forepart is traversed eight times and the other end portion four times. This additional repeated action of the pressure band may, as illustrated, be confined to the ball portion of the shoe. In this case it compensates for the smaller pressure per unit of area which is applied by the roll near the ball line where the band of pressure is long, because of the greater width of the shoe as compared with the greater pressure applied to the narrow portion near the toe where the pressure band is relatively short.

If it is desired to obliterate the ball line and to produce a rounded effect extending from the shank to the forepart of the sole, the action of the roll may be allowed to extend beyond the ball line part way into the shank, in which event the roll, by reason of its large diameter and its repeated short

movements to and fro over the ball line, serves to produce a well rounded juncture between the forepart and the shank.

As contributing to the production of thin edge and close edge shanks the invention further comprises a method consisting in skiving the margin of the outsole, on the side next to the upper, from the outer edge to a line beyond the line where the sole is to be stitched to the shoe, then laying the sole and stitching it to the shoe by a line of through-and-through stitches located outside of the inner edge of the skived portion so that the tightening of the stitches will tend to draw the margin of the sole toward the upper.

In another aspect the invention consists in applying to the shank portion continuous pressure during the treatment of the forepart only by the progressive pressure band as described. This pressure upon the shank, even if relatively light, tends materially to shape the shank portion of the shoe and, if not in itself sufficient for the shank shaping operation, tends to enhance the effect of the more powerful pressure later applied to complete the shank shaping operation. As illustrated, a pad or saddle extending from the ball line to the breast line is arranged to be applied to the shoe while it is being treated by the leveling roll. This saddle, being held by manually applied spring pressure against the shank portion of the sole, serves to press the margins of the sole down against the upper; to hold the shoe in place on the jack during the operation of leveling the forepart; to prevent displacement of the sole; and may, by the contour and pressure of its forward end, tend to emphasize the ball line when such an effect is desired. When, later, powerful pressure is applied to the shank portion, the desired effect is secured more quickly than is the case when the use of preliminary pressure on the shank during the leveling of the forepart is omitted.

The operation of shaping the shank portion only of the sole to the required transverse curvature to produce a close shank has been described as performed subsequent to the operation of leveling the forepart. It is to be understood, however, as within the invention to perform these operations or steps in either order.

In still another aspect, as applied to the manufacture of some styles of shoes, the invention consists in maintaining the forepart of the sole in a straight condition either transversely or longitudinally, or both, while the sole is being laid and also while the shank portion of the sole is being given the necessary transverse curvature to bring its margin into close relation to the upper. This result in sole laying is obtained by pressure applied perpendicularly to straight lines extending across the forepart, for example, as illustrated, by providing a flat, rigid plate

under the forepart of the sole. In the subsequent leveling operation on the forepart a substantially cylindrical roll of large diameter will be employed as described, so that the transverse flatness of the sole will be maintained or established if lacking, the roll having, of course, no lateral tipping movement. Under some conditions, however, for example when there is greater thickness of stock at the margins of the sole than at the center, in order to secure the desired result, that is, a transversely flat forepart, it may be necessary or desirable to employ a roll having a slight concavity or to impart a slight tipping movement to the roll.

In the subsequent operation of leveling the shank portion of the sole to secure the final transverse curvature and to force its margins closely against the upper, the flat condition already imparted to the forepart should be maintained and hence the operation as described for sole laying will preferably be repeated, the rigid plate being used so that the flat condition already imparted to the forepart will be maintained and enhanced.

These and other aspects of the invention will appear more fully from the following detailed description when read in connection with the accompanying drawings and will be pointed out in the appended claims.

In the drawings,

Fig. 1 is a perspective view of a lasted shoe ready for the laying of the outsole;

Fig. 2 is a sectional view of the margin of an outsole prepared for application to the shoe;

Fig. 3 illustrates the operation of laying the outsole upon the shoe;

Fig. 5 is a sectional detail of the shoe after the sewing operation;

Fig. 6 is a view showing the operation of leveling the forepart of the shoe and at the same time applying pressure to the shank portion;

Fig. 7 is an elevational detail of the roll and shoe shown in Fig. 6, the shoe being in section;

Fig. 8 is a plan view of the shoe and roll, the axis of the roll being parallel to the ball line;

Fig. 9 is a view of apparatus for leveling the shank portion of the sole, the leveling pad being shown in section;

Fig. 10 is a sectional detail of the pad and the shoe shown in Fig. 9 illustrating the distribution of pressure transversely of the shoe;

Fig. 11 is a view showing a cylindrical leveling roll for use in producing a flat forepart, the shoe being shown in section;

Fig. 12 is a side elevation partly in section of apparatus for laying and leveling the shank portion and producing a flat forepart;

Fig. 13 is a perspective view of the forepart plate shown in Fig. 12; and

Fig. 14 is a modification of the plate shown in Fig. 13.

In Fig. 1 is shown a lasted shoe ready to receive an outsole, the illustrated shoe having been made by the process set forth in United States Letters Patent No. 1,512,042, granted October 21, 1924, on application of J. H. Reed. A lasted upper 20 is held in place at the sides of the shoe by staples 22, the points of which do not penetrate an insole 24 but are clinched in the substance of the insole. The toe and heel of the shoe may be lasted in the usual manner and, as illustrated, were lasted by the use of a bed lasting machine. After lasting, the whole shoe bottom has, as illustrated, been subjected to a grinding operation by which the bunch of material 26 at the toe is reduced and small irregularities from other parts of the shoe bottom are removed and the leather roughened so that the outsole cement will hold better. Usually a small amount of filler or piece of filling material 28 substantially equal to the thickness of the upper and lining is placed on the forepart of the shoe bottom and then the whole bottom is coated with cement.

In preparing an outsole 30 for the shoe, it is channeled, the channel flap 32 remaining unturned, and the margin of the shank of the sole is reduced on its flesh side, as indicated in Fig. 2, by a cut on the dotted line *a*—*b*. This cut bevels the margin of the sole, the inner line of the bevel falling slightly inside the sewing line which is indicated by the line *c*—*d*. The extent of the bevel inwardly beyond the sewing line may be in the vicinity of one sixteenth of an inch.

The outsole, after being cemented on its flesh side, is placed on the shoe bottom and the shoe is put into a sole-laying machine, as shown in Fig. 3. In this machine, which is, for example, similar to that disclosed in United States Letters Patent No. 942,133, granted December 7, 1909, to Herman A. Davenport, the last is held by a heel pin 40 on a support 41 and by a toe rest 42 while pressure is applied to the sole by a pad 44, usually of rubber. The pad 44 rests on supports 46, 48, 50 and 52, which are so connected by equalizing mechanism 54 that the pressure is substantially equally distributed among the supports. The shank portion of the pad 44 is given a transverse curvature in excess of that required in the shoe shank so that the pressure is applied first and most heavily at the margin of the shank. Sufficient pressure is applied, however, to the forepart and heel part to secure the proper adhesion of the sole to the shoe.

The channel flap 32 is next turned up, the

last removed from the shoe and the shoe presented to a sole-sewing machine, which preferably will be a lockstitch machine of the type disclosed, for example, in United States Letters Patent No. 1,482,619, granted February 5, 1924, on application of James H. Reed, arranged to sew through and through the insole, upper and outsole, as indicated in Fig. 4, in which 60 is the horn, 62 the needle, and 64 a guide which runs along the base of the channel flap. The shank portion of the sewing line may lie at $c-d$ (Fig. 2) a little outside of the inner edge of the shank-reducing bevel $a-b$, and hence the thread tension as the 10 stitches are drawn tight will tend to bend the margin of the outsole toward the upper and will assist in securing and maintaining a close and thin edge shank. The outsole having thus been firmly secured to the upper and insole, the channel will be cemented and the channel flap laid as usual.

The shoe is now ready to receive treatment by which the final shape is given to the shank and forepart of the shoe bottom. 25 One step in this operation is represented in Figs. 6, 7 and 8, where the forepart of the sole is subjected to leveling pressure by the use of a roll 66 the action of which is confined to the forepart of the sole and is 30 progressive to and fro lengthwise of the shoe. As illustrated in Fig. 6, a Goodyear automatic leveling machine organized substantially as disclosed in Letters Patent of the United States No. 1,667,761, granted 35 May 1, 1928, on an application filed by myself and H. A. Davenport, may be utilized in carrying out the method described. To this end the movements of the jack about its pivot 68 are restricted so that relative 40 movement between the shoe and the roll 66 carried by a yoke 67 is confined to the forepart of the sole.

In order that the band of pressure applied by the roll to the forepart may be 45 wide lengthwise of the shoe, a roll of large diameter is employed, for example, a roll having a diameter greater than the length of the forepart. In the example illustrated, the roll is approximately eight inches in diameter; that is, the diameter of the roll approximates the length of shoe bottoms of the smaller sizes. One advantage of the use of such a roll consists in avoiding too 50 abrupt a leveling action at the end of the sole such as might bend the sole unduly, and another advantage is that the roll may be brought close to the ball line without danger of its going too far and dropping into the shank. Furthermore, the application of 55 pressure by the large roll in a broad band serves to reduce more effectively the bunch of upper material beneath the sole which may occur at the toe end of the shoe. Also, the roll, because of its diameter, is unable 60 to follow any of the minor irregularities of

the shoe bottom over which the outsole is placed. For example, there is frequently a cavity at the rear of the bunch of material at the toe. A large roll, however, with its broad band of pressure, bridges this and other irregularities of the shoe bottom and imparts the desired evenness to the forepart 70 of the outsole.

The roll 66 is mounted for limited axial movement on a shaft 68 in a carriage 69 which has rolls 70 engaging suitable guideways formed in the arms of the yoke 67. The carriage 69 is arranged for adjustment in the yoke so that the axis of the leveling roll may be arranged to extend in a direction parallel to the ball line, this adjustment being maintained by means at 72 for clamping the carriage to the yoke. The roll 66, when out of contact with the shoe, is maintained by a spring 71 toward that end 80 of the shaft 68 from which it tends to move, because of its inclination, when brought in contact with the shoe.

It is sometimes desirable to emphasize the ball line of the shoe to produce a desired style effect. The roll, in its repeated operations lengthwise of the shoe, stopping at the ball line, tends to give prominence to the ball line or line of transition between the forepart and shank. In case such prominence of the ball line is not desired the operation of the roll may be made to extend a little beyond the ball line to eliminate any line of demarcation between the forepart 95 and the shank.

The number of passages of the pressure band to and fro lengthwise of the shoe is indicated in Fig. 8 by a line 73, the pressure band being the area to which pressure is applied by the roll 66. In explaining these movements it will be convenient to refer to the roll as moving lengthwise of the shoe, though it is to be understood that in the machine as organized the shoe moves relatively to the roll. The line 73 represents the 100 number and extent of movements of the roll lengthwise of the shoe bottom, and also the path where the greatest pressure is applied by the roll when a small amount of tipping movement is imparted to it. The lateral separation of the lines is determined by the tipping movement of the roll, and if the tipping movement were reduced to zero for the purpose of producing a flat forepart the lines 105 would coincide. It will be noted that there are four passages of the roll over the entire forepart between the ball and the toe and that there are four additional movements which are confined to one end portion of the forepart. As illustrated, the rear portion of the 110 forepart near the ball line receives these additional passages of the roll which compensate for the fact that there is less pressure per unit of area when the band of pressure is long 115 widthwise of the shoe, as it is at the ball 120 portion. The lines 73 are spaced at 125 intervals of 130

tion, than when it is shorter, as it is on the portion nearer the toe.

The next step is the leveling of the shank portion of the sole which may be done by means of the apparatus shown in Figs. 9 and 10, which represent a sole laying machine of the kind shown in Letters Patent No. 942,133, above referred to. In this operation it is desirable to concentrate the action of the sole 5 pad upon the shank of the shoe and substantially to relieve the pressure upon the heel part and the forepart. This result may be obtained by so shaping the pad 75 that it does not bear on the end portions of the shoe bottom or by shortening the pad. As illustrated, 10 a rigid support 74 is provided beneath the pad, the effect of which is to concentrate the pressure upon the shank portion of the shoe. The pad, however, may still tip as a whole on a transverse pivot 76 located close to the surface of the shank so that the shank pressure will be suitably distributed. The transverse curvature of the shank portion of the pad is 15 preferably greater than that which is to be imparted to the shoe shank so that relatively greater pressure is applied to the margins of the shank than to the central portion, as indicated by arrows in Fig. 10, the effect being to force the marginal portion of the sole hard 20 against the last-supported upper at each side of the shank, with the result that a shapely and satisfactory close shank is produced. As illustrated in Fig. 9, it will be observed that the support 41 of the last pin 40 has been 25 lengthened so that the shoe is in a position with its toe tilted upwardly when pressure is applied by the pad. With the shoe in this position the shank pad tips correspondingly on its pivot 76 and the pressure is given a forward as well as a vertical component and is applied in a direction heightwise and forwardly with respect to the shoe, so that the 30 portions of the shank margin adjacent to the ball are adequately pressed against the upper. 35 The novel features embodied in the illustrated machine are not claimed herein but are claimed in my copending application Serial No. 246,852, filed January 14, 1928, as a continuation in part of the present application. 40

For the purpose of applying to the shank portion continuous pressure simultaneously with the treatment of the forepart of rolling pressure, apparatus illustrated in Fig. 6 may 45 be employed. This comprises a shank pad or saddles 78 which is operated by a lever 80 to apply, through suitable springs 82 attached to the opposite ends of the saddle, pressure to the shank portion of the sole sufficient to 50 hold the shoe jacked upon the heel pin 84 and toe rest 86 of the machine and to hold the shank portion of the sole pressed firmly upon the last while the toe part is being treated by rolling pressure as described. The saddle 78 55 and its operating mechanism may be, for ex-

ample, similar to that disclosed in United States Letters Patent No. 1,263,361, granted April 23, 1918, on application of W. C. Baxter. The pad 78 preferably extends from the ball line to the breast line of the heel-seat and its forward edge may be contoured to assist in forming a distinct ball line when such an effect is desired. The shoe may be jacked by the application of the saddle 78 as quickly as by other jacking means, and the application of shaping pressure to the shank portion of the shoe during the leveling of the forepart materially lessens the time required in the shank-leveling operation to produce the desired close shank. 70

If the bottom of the forepart of the shoe is to be substantially flat, a cylindrical roll such as that illustrated in Fig. 11 may be used, when the usual tipping movement of the yoke 67 will be eliminated or greatly reduced 75 so that the pressure of the roll will be substantially or nearly uniform at all points transversely of the shoe. In case the shoe materials require more pressure along the margins of the sole in order to produce a flat forepart, a slight amount of tipping movement may be imparted to the cylindrical leveling roll in order to increase its pressure along the margins of the sole. If it is desired 80 to impart a uniform convexity to the forepart, a roll such as that indicated in Fig. 7 may be employed, without tipping movement, the concavity of the roll preferably corresponding to the convexity desired in the sole. However, a roll of less concavity than the 85 convexity required for the sole may be employed provided the roll is given more or less tipping movement. It is to be understood, of course, that the machine is provided with the usual adjustments for controlling the tipping movement of the roll laterally of the shoe as well as for varying the relative 90 movements of the shoe and roll lengthwise of the shoe. 95

In leveling the shanks of shoes having flat foreparts it is important that the flat condition of the forepart shall be contributed to or at least not detracted from during this operation. To this end, and also for laying the sole of such a shoe, the apparatus shown 100 in Fig. 12 may advantageously be employed. Here a part of the mechanism of a sole laying machine of the type referred to is illustrated, having between the leather outer cover 90 of a rubber pad 92 and the pad itself a plate 94 which is flat but extends throughout the forepart of the shoe. Thus, while the shank portions of the shoe are being subjected to the action of the pad, either in the laying or leveling operation, to produce the transversely 105 curved close shank effect previously referred to, the forepart of the shoe is receiving pressure from the flat plate 94 which, if the shoe has already had its forepart leveled, will tend 110 to preserve its previous flat condition, and 115

if the shoe has not been leveled by the roll at the forepart, will tend to produce a flat condition of the forepart and render the forepart leveling operation easy. The subject-matter relating to the plate 94 is not claimed herein but is being claimed in a divisional application Serial No. 439,551, filed March 27, 1930.

The foreparts of some lasts are twisted; that is, the surface of the forepart, instead of being flat, is twisted somewhat about an axis extending lengthwise of the shoe. To meet this condition the construction shown in Fig. 14 may be substituted for the plate 94. Here the plate is made up of several sections or lags 96, 96, extending cross-wise of the forepart, of small extent lengthwise of the shoe, and connected by a flexible piece 98. With this construction, while each section or lag of the plate may remain transversely flat and straight, the plate, considered as a whole, may be twisted to conform to the twist of the forepart of the last.

Having thus described my invention, what I claim as new and desire to secure by Letters Patent of the United States is:

1. That improvement in methods of leveling the bottoms of shoes which consists in leveling the forepart of the sole by the use of a roll the periphery of which conforms substantially to the desired transverse contour of that portion of the sole, and leveling the shank portion of the sole by the use of non-progressive means having a greater transverse curvature than the shank.

2. That improvement in methods of leveling the bottoms of shoes which consists in leveling the forepart of the sole by the use of a roll which is substantially cylindrical in shape, and leveling the shank portion of the sole by the use of a pad so formed as to bend the margins of the sole.

3. That improvement in methods of leveling the bottoms of shoes which consists in leveling the forepart of the sole by the use of a roll too large in diameter for effective use in the shank while causing the roll to operate a greater number of times at one end of the forepart than at the other end, and thereafter leveling the shank portion of the sole by applying simultaneous pressure to all portions of the shank.

4. That improvement in methods of shaping the outsoles of shoes which consists in leveling the forepart only of the shoe, and after completing the leveling of the forepart leveling the shank part only of the shoe.

5. That improvement in methods of shaping the outsoles of shoes which consists in leveling the forepart of the shoe by pressure applied progressively to different portions thereof in succession, and leveling the shank portion by pressure applied to all portions thereof simultaneously.

6. That improvement in methods of leveling

shoe bottoms which consists in applying pressure to the forepart of the sole, to the exclusion of the shank, by the use of a roll of greater diameter than the length of the forepart to cause the pressure to be applied in a broad band extending transversely of the shoe bottom, and by relative movement of the roll and shoe causing said band to progress longitudinally of the shoe bottom between toe and ball line.

7. That improvement in methods of leveling shoe bottoms which consists in applying pressure to the forepart of the sole by the use of a roll having a diameter approximating the length of the forepart of the shoe to cause the pressure to be applied in a broad band extending transversely of the shoe, and by relative movement of the roll and shoe causing said pressure band to pass and repass lengthwise of the forepart while maintaining the front edge of the band always forward of the ball line.

8. That improvement in methods of shaping the outsoles of shoes which consists in leveling the forepart of the shoe exclusively by pressure applied in a transverse band which progresses lengthwise of the shoe and leveling the shank portion by pressure applied to all portions thereof simultaneously.

9. That improvement in methods of leveling shoe bottoms which consists in applying pressure to the forepart of the sole in a broad band extending transversely of the shoe, causing said pressure band to pass and repass lengthwise of the forepart while maintaining the forward edge of the band always forward of the ball line, and simultaneously maintaining continuous pressure on the shank portion.

10. That improvement in methods of shaping the outsoles of shoes which consists in leveling the forepart of the sole by a progressive leveling operation with pressure uniformly applied transversely of the sole and after completing the leveling of the forepart leveling the shank part of the shoe by pressure accentuated on both margins thereof simultaneously.

11. That improvement in methods of leveling shoe bottoms which consists in applying pressure to the forepart of the shoe bottom in a broad band extending transversely of the shoe bottom, causing said band to progress repeatedly to and fro longitudinally of the shoe bottom between the toe and ball line, and leveling the shank portion by powerful direct pressure applied to the entire shank portion simultaneously and concentrated upon its opposite margins.

12. That improvement in methods of leveling shoe bottoms which consists in applying pressure to the forepart of the sole in a broad band extending transversely of the shoe bottom, causing said band to progress longitudinally of the shoe bottom from toe to ball

line, and leveling the shank portion by pressure applied to the entire shank portion simultaneously and concentrated at the margins of the shank.

13. That improvement in methods of leveling shoe bottoms which consists in applying pressure to the forepart in a broad band extending transversely of the shoe bottom, causing said band to progress longitudinally of the shoe bottom from toe to ball line, and then leveling the shank portion by direct pressure applied to the entire shank portion simultaneously and overlapping the ball line to obliterate any line of demarcation between the shank and ball.

14. That improvement in methods of leveling shoe bottoms which consists in applying pressure in a broad band extending transversely of the shoe, causing the pressure band to progress from toe to ball line and back, and meanwhile maintaining the shank portion under constant pressure.

15. That improvement in methods of shaping the outsoles of shoes which consists in leveling one part of the sole by a progressive leveling operation and after completing the leveling of that part leveling another part of the sole by pressure applied to said other part as a whole.

16. That improvement in methods of leveling shoe bottoms which consists in applying pressure to the forepart of the sole in a broad band extending transversely of the shoe, causing said pressure band to pass and repass lengthwise of the forepart while maintaining one edge of the band always forward of the ball line, simultaneously maintaining unvarying pressure on the shank portion, and then subjecting the entire shank portion to pressure of greater intensity.

17. That improvement in methods of making shoes which consists in preparing a shoe having an upper lasted inwardly upon an insole, laying an outsole, attaching the outsole, upper and insole together by through-and-through stitches, leveling the forepart by subjecting successive portions thereof lengthwise of the shoe to rolling pressure, and thereafter leveling the shank part by pressure applied to both margins of the shank simultaneously and more strongly to the margins of the shank than to its central portion.

18. That improvement in methods of leveling shoe bottoms which consists in applying pressure simultaneously to all portions of the shank in an upward and forward direction with respect to the shoe to produce a close shank in the curved portion of the shank adjacent to the ball.

19. That improvement in methods of leveling shoe bottoms which consists in applying pressure to the forepart of the sole in a broad band extending transversely of the shoe bottom, causing said band to progress longitudinally of the shoe bottom between the toe and the ball line, and leveling the shank por-

tion by pressure applied to the entire shank portion simultaneously, said pressure being applied in a direction forward and heightwise with respect to the shoe to force the sole against the upper in the curved portion of the shank adjacent to the ball.

20. That improvement in methods of leveling the bottoms of shoes which consists in operating upon the forepart only of the sole with rolling pressure repeated a greater number of times at one end of the forepart than at the other end.

21. That improvement in methods of leveling shoe bottoms which consists in applying pressure to the forepart of the sole in a band extending transversely of the shoe bottom, causing said band to progress longitudinally of the shoe to and fro between the toe and the ball line, and causing successive traverses of the pressure band upon one end portion of the forepart to the exclusion of the other end portion.

22. That improvement in methods of leveling shoe bottoms which consists in applying pressure to the forepart of the sole in a broad band extending transversely of the shoe bottom, causing said band to progress repeatedly longitudinally of the shoe from the toe to the ball line and back, and causing successive repeated traverses of the pressure band upon one end portion of the forepart to the exclusion of the other end portion.

23. That improvement in methods of leveling shoe bottoms which consists in applying pressure to the forepart of the sole in a band extending transversely of the shoe bottom, causing said band to progress longitudinally of the shoe from the toe to the ball line and back, and causing successive traverses of the pressure band upon the ball portion of the forepart to the exclusion of the toe portion.

24. That improvement in methods of leveling the bottoms of shoes which consists in applying holding pressure to the shank portion of the sole of the shoe, and while the shank is thus held, leveling the forepart only of the sole.

25. That improvement in methods of leveling the bottoms of shoes which consists in applying a saddle over the shank portion of the sole to assist in holding the shoe and in shaping the shank, and while the saddle is thus applied, subjecting the forepart only of the sole to rolling pressure.

26. That improvement in methods of leveling the bottoms of shoes which consists in applying a saddle over the shank portion of the sole, applying rolling pressure to the forepart only of the sole while the saddle is thus applied, and thereafter removing the saddle and applying leveling pressure to the shank portion of the sole.

In testimony whereof I have signed my name to this specification.

ERASTUS E. WINKLEY.
